DEVICE FOR DETECTING BLOWN FUSES

Adolph Lang, New York, N. Y.

Application May 18, 1951, Serial No. 226,997

1 Claim. (Cl. 200—121)

1

My present invention relates to a method of and a device for facilitating the discovery of a blown electric safety fuse among a number of such fuses arrayed on a panel, in a fuse box or on some other support.

In private residences, in apartment houses and particularly in factories and other commercial establishments the blowing of a fuse due to accidental overloading of a power line is often a source of considerable annoyance, as well as costly delay, on account of the time required in identifying the destroyed fuse among a group of intact ones located close by, in view of the fact that a large number of such fuses are usually placed next to one another in poorly illuminated locations such as basements, stairways and the like.

The general object of my invention is to provide a method of and means for avoiding the above inconveniences by greatly facilitating visual inspection of fuses and enabling the virtually instantaneous determination of the intact or blown condition of a fuse even at considerable distance and under poor lighting conditions.

In accordance with the invention I provide an attachment having a phosphorescent surface adapted to be so positioned on the fuse as to be conveniently visible from without (at least in the excited state) while being exposed to light rays from the spark caused by the melting of the fusible metal strip by excessive line current. I have found that the glow of the phosphorescent surface, when thus excited, will remain visible for a sufficient length of time (up to several hours) to indicate to an observer the fact that a flash has occurred in the fuse.

The invention will be described with reference to the accompanying drawing in which:

Fig. 1 is a longitudinal section through a conventional electric fuse, provided with a phosphorescent attachment representing an embodiment of the invention;

Fig. 2 is a side elevation of the attachment shown in Fig. 1;

Fig. 3 is a rear view of the fuse with attachment shown in Fig. 1;

Fig. 4 is a front view of the attachment;

Fig. 5 is a longitudinal section through a fuse similar to that of Figs. 1 and 2 (but taken at right angles to the section of Fig. 1), the fuse being provided with a modified phosphorescent attachment according to the invention;

Fig. 6 is a front view of the fuse with attachment shown in Fig. 5; and

2

Fig. 7 is a section taken on the line 7—7 of Fig. 5.

Referring first to Figs. 1—4, there is shown a conventional safety fuse 10 comprising a body 11 of insulating material, a glass housing 12 receiving part of said body, a metal shell 13 threadedly engaging the housing 12 and bearing against a shoulder 14 of the body 11 to keep same in engagement with the housing 12, and a fusible strip 15 having one end conductively secured to central terminal 16 and having its other end in contact with the shell 13.

Mounted on the front face of the housing 12 is an attachment 20 comprising a ring 21 slotted at 22a, 22b and 22c to provide two resilient wings 23a, 23b adapted to engage the flange 17 of the housing; it will be noted that with this arrangement a tight fit may be obtained even in the event of substantial variations of fuse size, this being an important advantage on account of the fact that fuses even of common manufacture are found to vary considerably in circumference. Lodged in the ring 21 are two parallel, transparent disks 24, 25 (e. g. of resinous material) separated by a spacing ring 26. Inner disk 25 carries a phosphorescent coating 27 facing the outer, protective disk 24.

When the fuse 10 is overloaded, the strip 15 will melt with a flash causing intense light to penetrate the glass housing 12 and the disk 25, thereby exciting the phosphorescent layer 27 to prolonged luminescence. From the glow of the surface 27 an observer will then be able to determine the fact that the fuse has been put out of commission. Ring 21, which is of opaque material, acts as a light shield to prevent similar attachments on adjacent fuses from becoming excited upon blowing of the fuse 10.

In Figs. 5—7 the attachment 20 has been replaced by an attachment 30 in the form of an annular insert 31 bearing on its inner surface a phosphorescent coating 37. The insert 31 fits snugly inside the chamber 18 of the fuse housing 12 (see Fig. 1) and is thermally shielded from the fusible strip 15 by a transparent disk 34. Disk 34 is preferably cut away at 32a, 32b (Fig. 7) and provided with stepped portions 33a, 33b to establish communication between the chamber 18 and the space 19 adjacent the strip 15.

The operation of the device shown in Figs. 5—7 is in principle identical with that of the one described in connection with Figs. 1—4, with the additional advantage that the strip 15 remains visible as clearly seen in Fig. 6. The condition of the fuse may thus be readily ascertained in the

normal manner after the luminescence of the layer 37 has vanished. A similar advantage may, of course, be had with the attachment of Fig. 1 by omitting a central portion of the layer 27.

The annular insert 31, being opaque, again acts as a light shield to prevent excitation of adjacent fuse attachments.

Although the invention has been described with reference to only two specific embodiments, it is to be understood that the same may be modified in various ways without thereby departing from the scope of the appended claim. For example, some or all of the light-transmissive members of the attachments described, such as disks 24, 25 and 34, may be made translucent instead of transparent, if desired.

I claim:

As a new article of manufacture, an attachment for indicating the blowing of an electric fuse of the type having a closed housing provided

with a window surrounded by a transparent or translucent annular flange, said attachment comprising a ring of opaque material slitted perimetricaly and in axial direction, thereby forming 5 a pair of outwardly movable wings each extending over a major fraction of a quadrant of said ring and adapted resiliently to engage said flange, a disk of light-transmissive material surrounded by and supported on said ring, and a phosphorescent coating on said disk, said ring 10 shielding said coating from excitation by a flash from an adjacent fuse.

ADOLPH LANG.
